VERTICAL LIFT CONTROL SYSTEM

Le Roy H. Kiesling, Bay Shore, N. Y.

Application October 6, 1949, Serial No. 119,903

31 Claims. (Cl. 187—29)

1

The present invention relates to vertical lift systems of the type wherein a car operating in a vertical hatchway is raised or lowered from one floor or level to another. It is particularly concerned with the provision of improved control systems for such vertical lift systems for enabling them to be employed primarily as elevators or dumbwaiters, and for greatly improving their usefulness.

The present application is a continuation-in-part of my application Serial No. 31,672 filed June 8, 1948, now abandoned.

Heretofore, dumbwaiters of the motor-propelled type have lacked features of "memory circuits" for delayed response to calls signalled before readiness of the system to perform the ordered function. Accordingly, an attendant at one station of such a system would spend a great amount of time at the dumbwaiter station, persistently pressing a call button, until the eventual response of the system, and much time which otherwise could have been used for productive effort was consumed in this way.

In my U. S. patent application Serial No. 794,955 filed December 31, 1947, now Patent No. 2,493,293 of January 30, 1950, I have set forth a control system for two-station dumbwaiters wherein sending circuits and memory features are provided, such that an operator may load the dumbwaiter car at one of the stations and depress two buttons, and then close the dumbwaiter doors with the assurance that the dumbwaiter car will proceed to the other station, wait there for an operator to unload it, and thereafter return to him automatically when the operator at the other station has completed his task of unloading and/or loading the car.

Similarly, in my system of application Serial No. 794,955, an operator at one station may signal a "call" to bring the car to him from the other station, with the assurance that this signalled call will be honored. If the dumbwaiter system is in readiness for immediate response to the call at the time it is signalled, the car will proceed at once to come to the station from which the operator has signalled. If the dumbwaiter system is not in readiness for immediate response to the call, then a holding circuit condition is set up which will survive all intervening functions which may occur in the system, so that upon full preparation of the system to permit the car to come to the station at which the signal was given, it will proceed automatically to do so.

It is an important object of the present invention to provide a vertical lift system serving not

2

only two terminal stations but also one or more intermediate stations, and embodying the operational features described above for the two-station system of application Serial No. 794,955, as well as further features to be set forth below.

It is a further important object of the present invention to provide a vertical lift system serving two terminal stations and at least one intermediate station, and so arranged that call signals can be registered at any one or more of the stations and will be stored in "memory" circuits and given ultimate effect in the turn dependent upon the direction of movement of the car and the order in which the calling stations are reached in such direction of movement. According to this object of the invention, if the car were moving toward the fourth station of a system to answer a call signalled from that station, and during its movement between the first and second stations, call signals were placed for the first, second and third stations, whatever the order of signalling of these three calls the car would stop at the second station, then at the third station, then at the fourth station, and then would proceed non-stop to the first station. If a still further call were registered at one of the intermediate stations after the car had proceeded upward beyond such station and before it had returned on its mission to the first station, the car would again be compelled to stop at the intermediate station, as the further call signalled therefrom would also take precedence over the first-station call, being earlier reached by the descending car.

Yet another object of the present invention is the provision of a vertical lift system serving two terminal stations and at least one intermediate station, the control system for this vertical lift system being so arranged that the car can be made to travel non-stop from an initial station to a selected destination regardless of any intervening-station calls previously or subsequently placed, and regardless of the direction of movement prior to arrival at said initial station, such express or priority movement of the car being accomplished at the will of a sending operator, i. e. an operator having the car at his disposal at the initial station. This feature is needed in order to insure the most efficient use of a multi-station dumbwaiter system, in that an operator loading the car at an initial station for a known destination is permitted to prevent any interruption of the car movement until it has reached that destination and been unloaded there.

If an operator at the first floor of a four-story building has material to be moved to the third

floor, for example, and that material amounts to three loadings for the car, the first floor operator can load the car and send it to the third floor, so that it proceeds to that floor regardless of any calls which may be stored in the system or may be placed in the interval of movement. Likewise, an operator at the third floor may unload the car and/or load it with material for the first floor, and may send it directly back to the first floor, and this routine can be repeated until the entire stock has been moved. If this feature were not provided, the car with its load of material for the predetermined destination could be caused to make time-consuming and entirely unproductive trips and/or stops at intervening stations, and thus the efficiency of the system for dumbwaiter purposes would be materially impaired.

Still a further object of the invention is to provide a control system for a lift system having a car arranged to serve two terminal stations and at least one intermediate station, and so arranged that the movement of the car can be controlled through the manual operation of control switches located within the car, and arranged in such a way that the express or priority movements as described above can be achieved through the operation of selected express buttons in the car, the arrangement being such that calls may nevertheless be placed at any one or more of the stations served by the system, and these will be stored until the car can come to these call stations in its direction of movement and free from priority requirements inserted through sending signals.

In fulfilling this last-stated objective, a control system is achieved which is suited not only for dumbwaiter purposes but for certain freight and passenger elevator requirements as well, the express control button switches in the car being available to one operating them on the car when it is fully loaded for a remote station so that he can postpone the stops of the car at the calling stations until the trip has been completed and the car load has been reduced to such an extent that the car can serve a useful purpose in stopping at the calling stations.

Yet a further object of the present invention is to provide a vertical lift system for upper and lower terminal stations and at least one intermediate station, the system being arranged in such a way as normally to have calls at a plurality of stations answered in the turn corresponding to their order as reached in the direction of travel in which the car is in progress, but with special emergency call means for bringing the car to a station immediately notwithstanding other calls for the car, the other calls being held stored nonetheless until they are answered.

The foregoing objects and features of the invention will be enlarged upon, and further objects and features will become apparent in the detailed description which follows, taken with reference to the drawings, wherein:

Figs. 1 and 2 are a schematic hatchway diagram and a circuit diagram, respectively, of a three station embodiment of the invention having fixedly located send switches and regular call switches, only;

Figs. 3 and 4 are hatchway and circuit diagrams, respectively, of a four-station embodiment of the invention including emergency call switches and a set of car switches; and

Fig. 5 is an illustration of a retiring-cam fea-

ture modification applicable to either of the foregoing systems.

Fig. 1 shows the general scheme of a three-station dumb-waiter hatchway, the car 1 being illustrated as between stations II and III. An access door is provided at each station, vertical-sliding access door 8 at station I being illustrative, and the other doors being omitted for simplifying the drawing. Each access door is provided with a switch, e. g. switch 19, arranged to be held closed when the access door is entirely closed, and to be open at all other times. Well known mechanism may be provided to retain the doors locked closed except when the car is present, but such mechanism, not being part of the present invention, is not shown in the drawing.

Three cam-operated switches are provided at each terminal station, i. e. stations I and III, and two cam-operated switches are provided at the intermediate station II. Switches 15, 25 and 35 are normally open switches for the car-send switch circuits. Switches 17 and 37 are normally closed lower and upper limit switches for arresting the car at the respective terminal stations. Switches 16 and 36 are supplementary normally open switches at the terminal stations, and switch 26 is an intermediate-station double-throw switch. To simplify the drawing, two cams 5 and 6 are shown on opposite sides of the car 7, but in practice a single cam or a set of cams may be provided at one side or the rear of the car, if preferred.

In Fig. 2, a set of manual control or "order" switches is provided at each station, each set including one button switch for each floor or station served by the dumbwaiter system. Each of these switches is designated by a two-digit number, the first digit representing the station at which the switch is located, and the second digit representing the station to which that switch is to direct the car. E. g., switch 12 is a switch at the lowermost station I for sending the car to station II, and switch 23 is a switch at the third station for calling the car to that station.

Two main relays 50 and 60 are provided for controlling the dumbwaiter car propulsion circuits, a normally open contactor 51 on relay 50 being connected to the motor coils for permitting the descent of the car, and a normally open contactor 61 on relay 60 being connected to the motor coils for operating the motor in the direction to raise the car. The motor and the connections therefor are omitted, these connection arrangements being well known in the art.

A quick-opening, delayed-reclosing relay 70 with a normally closed contactor 71 is provided for retention of the car at a station for a reasonable time after arrival. This relay is connected to the coil circuits of relays 50 and 60 for blocking their operation during the predetermined interval after arrival of the car at a station.

Direction-control relays 80 and 90 are connected to relays 50 and 60, respectively, and arranged to be energized to block the operation of the respective main relays. These relays have normally closed contactors 81 and 91, each connected by cross-connections in the coil circuit of the opposite relay. Further normally closed contactors 82 and 92 are connected in series with the coil circuits of the respective main relays. Normally open contactors 83 and 93 on these relays are arranged in holding circuits.

Contactors 81 and 91 of these relays are arranged to prevent both relays from being energized simultaneously, energization of either of

these relays resulting in the blocking of the energization circuit of the other. By virtue of the connection of contactors 82 and 92 in series with the coils of relays 50 and 60, energization of relay 80 blocks the coil circuit of relay 50, and energization of relay 90 blocks relay 60.

A pair of triple-contactor relays 100 and 110 are provided with their coils connected to the contactors 27 and 28, respectively, of the double-throw intermediate station switch 26. These relays serve with the switch 26 to provide the effect of a triple-pole, double-throw switch. All contactors of these relays are normally open. The double-throw switch 26 is arranged as shown in Fig. 1 in such a way that contactor 27 is closed when the car is above, and contactor 28 is closed when the car is below station II. Furthermore, when the car descends to station II it switches over the mechanism to open contactor 27 and close contactor 28; and when it ascends to station II, it switches over the mechanism to open contactor 28 and close contactor 27. With relays 100 and 110 connected as shown in Fig. 2, contactors 101, 102 and 103 are closed when contactor 27 is closed; and contactors 111, 112 and 113 are closed when contactor 28 is closed.

Relays 120 and 130 are provided for holding circuits for bringing the car to the intermediate station III, relay 120 being actuatable for a descent of the car from station III, and relay 130 being actuatable for an ascent of the car from station I. Supplementary relays 140 and 150 are provided in connection with relays 120 and 130, for reasons which will subsequently be made evident.

A relay 160 is provided for holding a circuit for causing ascent of the car to the upper terminal station III, and a relay 170 is provided for causing descent of the car to the lower terminal station I. A pair of priority-order relays 180 and 190 are provided for super-control of the car movements according to those car sending orders requiring the car to proceed from a terminal station past the adjacent station (in the case of a three-station system, past the intermediate station II) to a remote station, and according to all send orders placed at the intermediate station II.

Relay 180 is connected with switches 13 and 23, and with relay 160, to cooperate with the latter relay in response to a signal placed through either of these switches and to temporarily forestall any other operation of the car than that signalled through one of these switches. Relay 190 similarly is connected with switches 21 and 31, and with relay 170, to cooperate with the latter relay in response to a signal placed through either of these switches and to forestall temporarily any other operation of the car until such a priority order has been fully carried out.

The operation of the dumbwaiter system of Figs. 1 and 2 may best be described by considering a few examples of orders or demands which may be made through the station order button switches, and the operation which ensues. For a first example, assume that the car is positioned at the first floor station, i. e. station I, and that the operator there loads the car with material to be moved to station II; and further assume that this operator at station I wishes to recall the car immediately after the delivery to station II, as for sending further material to station II or another station. Upon completion of the loading of the car for station II, the operator closes the car gate (omitted from Fig. 1 for simplicity), with the result that the cargo is protected and the gate contactor switch 9 is closed. If the operator closed

the access door 8 also, immediately he would render the car subject to immediate response to a call of the car to another station.

Before closing the sliding door 8, and thus while in full command of it, the operator momentarily depresses buttons 12 and 11, the former for sending the car to station II, and the latter for recalling it. The order of depressions of these switches is inconsequential, the present system being made to take into account the likelihood of careless operation and to safeguard against improper operation due to failure to observe special order procedures. By way of illustration of the tolerance of the system for operator carelessness, suppose the operator signals the recall order by depression of button 11 first, and then presses button 12.

The car being at the lower station I, cam 5 holds switch 15 closed, and cam 6 holds switch 16 closed and switch 17 open. Through switch 16, a circuit is established from the positive supply conductor through conductor 203, through normally closed contactor 91, and through the coil of relay 80 to the negative supply conductor. Relay 80 is therefore energized so long as the car remains at station I, blocking any energization of relay 50 and hence any downward motivation of the car. Moreover, the car being below station II, switch 26 is in the throw condition with contactor 27 open and conductor 28 closed, and the contactors 111, 112 and 113 of relay 110 are accordingly closed.

The depression of button 11 provides current flow from the positive conductor, through conductors 205 and 249, through contactor 83 and conductor 207, and through the coil of relay 170 to the negative conductor, so that relay 170 is actuated. The consequent closure of contactor 173 establishes a holding circuit from the positive conductor, so that this circuit condition is maintained after the release of button 11.

The circuit established for bringing the upper end of the coil of relay 170 to the potential of the positive supply conductor is also effective to place conductor 209 at the positive supply voltage, and so long as relay 180 remains inactive and contactor 186 remains closed, conductor 211 is given the same voltage. Through contactors 171 and 172 which now are held closed, conductors 213 and 215 also are held at positive potential. Current flow through conductor 215 is blocked by open contactor 81, but current is carried through conductors 213 and 217, contactor 121 and conductor 219 to the coil of relay 140, and through this coil to the negative supply conductor. Relay 140 is therefore actuated, and the positive supply potential is then extended through conductor 221 and contactor 141, and through conductor 223 and contactor 122, to conductors 225 and 227, current flow through the latter being blocked by the open contactor 82 of energized relay 80.

Now, upon the closing of car-sending button 12, a circuit is established from the positive conductor through conductor 229 and conductor 231, through closed contactor 112 and conductor 233, to the coil of relay 130, which is therefore energized. A holding circuit for relay 130 is now established through contactor 111 and conductor 235 and contactor 135, so that relay 130 is retained in actuated condition after the depression of switch 12.

A circuit for the energization of relay 60 is now completed through relay 130. This circuit may be traced over either of two routes from the 75 positive supply conductor to contactor 133, one

route being through contactor 187, conductor 237, contactor 187, conductor 239, conductor 241, contactor 113 and, conductor 243; and the second of the two routes being through switch 16, conductor 203, conductor 245, and contactor 134. Through contactor 133 and conductor 247 and contactor 92 the positive-potential supply circuit is completed to the upper terminal of the coil of relay 60, so that this relay is energized and the motor commences lifting the car toward station II.

As the car rises upward, cam 6 first clears switch 17 and later clears switch 16. No circuit being dependent upon switch 17 so long as relay 80 is energized and contactor 83 is closed, the closing of this switch is without any immediate effect. The ensuing opening of switch 16 prevents the supply of current through conductor 233 to the coil of relay 80, but the current path through contactors 187 and 197, conductors 239 and 241, contactor 113, conductor 243 and contactor 134 remains intact and keeps relay 80 energized.

As the car reaches station II, cam 6 engages the double-throw switch 26 and opens contactor 28, at the same time causing the closing of contactor 27. Relay 110 is thus deenergized and relay 100 is energized. The opening of contactor 111 interrupts the holding circuit of relay 130, so that this relay also is deenergized. The supply of current through contactor 133 and conductor 247 is thus broken, so that the energization of relay 60 ceases and the car is stopped at station II.

At the same time that the opening of contactor 133 breaks the circuit through the coil of relay 60, contactor 134 opens and breaks the supply of current through conductor 245 and contactor 91 to the coil of relay 80. This relay is therefore deenergized just simultaneously with relay 60.

In accordance with the principles set forth in my copending U. S. patent application Serial No. 794,955, filed December 31, 1947, the quick-opening, delayed-reclosing relay 70 is interconnected with relays 50 and 60 in such a way that the actuation of either of these motor control relays results in the immediately subsequent actuation of relay 70, so that contactor 71 is opened. The opening of contactor 71 is prevented from having any immediate effect upon the actuation circuit of the then effective motor control relay, by the arrangement of normally open contactors 53 and 63 to insure that contactor 71 be shunted from the time immediately before the opening of contactor 71 to the end of the period of actuation of the effective motor control relay. Then, however, with the opening of the actuation current through the coil of the effective motor control relay, both of contactors 53 and 63 are open, so that contactor 71, being held open for a predetermined period of time by the action of delay mechanism 72, positively blocks the energization of a motor control relay during this period and thus compels the car to wait at the station at which it has arrived before responding to any further signal, whether new or stored from a previous button depression.

The deenergization of relay 60 simultaneously with that of relay 60 does not break the holding circuit of relay 170, because upon the commencement of upward movement of the car, lower limit switch 17 reclosed and held complete a current path from the positive supply conductor through contactor 173 and conductor 249. Immediately following the deenergization of relay 80, however,

and as a consequence thereof, the closing of contactor 81 completes the energization circuit for relay 90, as traceable from the positive supply conductor through contactor 173, conductor 249, switch 17, conductor 239, contactor 163, conductor 211, contactor 172 and conductor 215. At the same time, the closure of contactor 82 brings the upper end of the coil of relay 50 to the positive supply potential, the circuit being traceable from the positive supply conductor through contactor 173, conductor 249, switch 17, conductor 239, contactor 186, conductor 211, contactor 171, conductors 213 and 217, contactors 141 and 122, conductor 227, and contactor 82 to the coil of relay 50.

As the restoration of contactor 82 to its closed resting position cannot occur instantaneously upon the cessation of current through the coil of relay 50, but necessarily results a moment later, and since a still further moment is required for the response of relay 53 after closure of contactor 82, contactor 53 cannot be closed before contactor 83 has opened, so that the continuity of the circuit shunting contactor 71 is momentarily broken, satisfying the requirements for relay 70 to insure the delay before the car can again be started on its way.

Now, when the predetermined delay interval has elapsed after cessation of the current through the coil of relay 70, mechanism 72 allows the contactor 71 to resume its normally closed condition. Upon this reclosure, assuming that the series-connected gate and door switches 9, 19, 29 and 39 are then closed, the current path through the coil of relay 50 and on to the negative supply conductor is completed, so that relay 50 starts the car on its downward travel in obedience to the station I recall order being held by relay 170.

As the car starts downward, it again switches over the arms of switch 26, causing the opening of relay 100 and the closing of relay 110. This closing of relay 110, of itself, is unable to establish any complete circuits, as will be seen by tracing the connections to each of its contactors 111, 112 and 113. However, it does render the up-direction holding circuits receptive to any up-direction call signal which may be given through button 22.

Relay 50 remains energized and the car accordingly is driven downward until cam 6 engages switch 17, opening this switch and interrupting the energization of relay 173, relay 90, relay 143, and relay 50, and therefore arresting the descent of the car at the position of the access door at station I.

Car cam 6 having engaged and closed switch 16 just prior to the stopping of the car, and relay 90 having been deenergized immediately thereafter by the opening of switch 17, with consequent reclosure of contactor 81, the circuit from the positive supply conductor through switch 16, conductor 233, and contactor 81, being thus completed, energizes relay 80, assuring readiness of the car system to respond to an up-direction order, only.

Throughout the foregoing description of an example of the operation of the dumbwaiter system of the present invention, it has been assumed that no conflicting calls were signalled into the system. It will be readily apparent, however, that the system must be receptive to a call signal at any time, and that such a call signal may be inconsistent with other signals to which the car must respond. A fundamental feature of the

present arrangement is that it possesses memory characteristics for all calls which may be placed, and that in the absence of send orders, the car will be made to respond to these orders in the turn determined by its location and direction of travel. A send order, on the other hand, is given priority over all call orders.

The send order by which the car was sent to station II in the foregoing illustration insured that the car would go directly to station II and stop there, as this was the first station in the only possible direction of travel of the car from station I. If a call order has been signalled from station III at the same time that the send order was signalled at station I for sending the car to station II, the system would require no special priority arrangements for the response to the send order first, since in this instance the send order to station II is an order calling for movement of the car to the next station in its required direction of travel (and only possible direction from station I).

To illustrate a condition requiring a special priority circuit operation, take an example with the car located at station I, and suppose the operator at station I depresses switch button 13, signalling an order for sending the car to the third station.

Now, in view of the fact that a call order could be signalled at station II before this station III send order is placed, or at the same time as the send order, or thereafter but before the car has passed beyond station II en route to station III in response to the send order, the present invention includes arrangements for insuring that the car will proceed directly to station III notwithstanding the call ahead, so that the send order is given full priority. This send order priority is accomplished by the operation of the station III destination priority relay 180, along with the holding relay 160 which would be actuated in any case for bringing the car to station III. Note that a station III call order, placed through switch 33, would actuate merely relay 160, having no effect on relay 180, and such a call order would not take precedence over a station II call.

While the car is at station I, cam 5 holds switch 15 closed, so that a send order can be placed at this station. The depression of switch 13 completes the circuit for actuation of relay 180, through conductors 253, 255, 257 and 259, contactor 184, and conductor 261. Relay 160 is thereupon energized through contactor 181, conductor 263, upper limit switch 37 and conductor 265, and once energized, relay 160 remains energized through the holding circuit provided by contactor 161 in series with limit switch 37.

The down-direction blocking relay 80, initially energized through switch 16, conductor 263 and contactor 91 while the car is at station I, is retained energized through conductor 267, contactor 196, conductor 269, contactor 163 and conductor 271 for so long as upper limit switch 37 remains closed, and hence until the car reaches its destination, station III.

Relay 180 having been energized and having caused the actuation in turn of relay 160, a holding circuit is established for retaining relay 180 energized, this circuit being traced through contactor 161, limit switch 37, conductors 265 and 267, contactor 196, conductor 269, contactor 162, conductor 273 and contactor 182.

So long as the car is below station II, contactor 28 is closed and relay 110 is energized.

Through energized relay 180, a circuit is estab-

lished for the energization of relay 60, and therefore the motor operates to lift the dumbwaiter car toward station III. The circuit through which the coil of relay 60 is supplied is traced through contactor 183, conductor 275, conductor 247 and contactor 92.

From the foregoing explanation, it will be apparent that the depression of the station III send button 13 energized relay 180, and through this relay, further relays 160, 80 and 60 were energized. Through energized relay 160, two holding circuits were established—one through contactor 161 to hold relay 160 energized so long as the upper limit switch 37 remains closed, and one through contactor 162 and conductor 273 holding relay 180 energized so long as the upper limit switch remains closed. It will be apparent, further that the interconnections among these four energized relays are independent of switch 26 and relays 100, 110, 120 and 130. In view of these facts, the car is propelled upward continuously past intermediate station II to its destination, i. e. to station III, where it opens limit switch 37, causing the deenergization of relays 160 and 180, and through the latter, of relays 60 and 80. With the opening of relay 60, the motor stops so that the car is thereby brought to a halt at station III.

The priority accorded a send order by the priority relays 180 and 190 (the former for send orders directing the car to station III, and the latter for send orders directing the car to station I) is made strikingly apparent if it is assumed that an operator at station II signalled a call order through a depression of switch 22, at a time while the car was below this station. But for the plan of priority accorded a send order, that call should be answered by a halt of the car at station II before it proceeded on to station III in response to the send order as just described.

The car having been below station II at the time switch 22 was momentarily depressed, switch 29 was in the throw position with contactor 28 closed, and relay 110 was energized. A circuit accordingly was momentarily completed through switch 22, conductor 231, contactor 112 and conductor 233, energizing relay 130. Thereupon a holding circuit for relay 130 was established through contactor 111, conductor 235 and contactor 135, retaining relay 130 energized. With relays 130, 180 and 160 energized, a circuit is provided for energization of relay 120, through contactor 185, conductor 277 and 279, contactor 136 and conductor 281 and 283. Upon the energization of this relay 120, contactor 125 closes to shunt the path through conductor 279, contactor 136 and conductor 281, so that the energization of relay 120 can survive beyond the deenergization of relay 130 which must occur as the car passes station II, opening contactor 28 and deenergizing relay 110.

Since the circuit conditions set up through the energization of relay 180 caused the energization of relay 60 independently of any of relays 160, 110, 120 and 130, the setting up of these holding circuits in relays 130 and 120 is prevented from affecting the operation of the dumbwaiter car propulsion system until it has proceeded directly to station III, as ordered by the operator at station I through depression of sending switch 13 while the car was at his station.

After the system has performed according to this send order and the car has reached station III, however, it must respond to the station II call. The energization circuit for relay 120, though originally established through contactor 185 and conductor 277, survives after the opening of con-

75

tauctor 185 at the time of arrival of the car at station III, because relay 100 is energized through contactor 27 during the progress of the car above station II, and a shunt positive supply circuit is therefore provided through contactor 101 and conductor 285.

It will be readily apparent that this holding circuit for relay 120, including contactor 101, conductor 285 and contactor 125, is just the same in all respects as would have resulted from a momentary depression of the button 22 at a time when the car was at rest at station III. The car being now at station III and relays 100, 120 and 90 being energized (the latter being supplied coil current through switch 36, conductors 287 and 289 and contactor 81); a circuit is established from the positive supply conductor through contactors 187 and 197, conductor 241, contactor 103, conductors 291 and 293, contactor 123, conductor 227 and contactor 82. Through this path, relay 50 becomes energized when the predetermined time for the reclosing of contactor 71 has elapsed and switches 9, 19, 29 and 39 are closed.

At the energization of relay 50, the motor operates in the direction to cause the descent of the car, and this continues until the car reaches station II, cam 6 (Fig. 1) engaging switch 76 and opening contactor 27, and causing the deenergization of relay 100. This produces multiple breaks in the positive supply circuit to the coil of relay 50, one break being caused by the opening of contactor 103 in the circuit between contactor 197 and conductor 227, and a further break being made in the circuit by the opening of contactor 123 when relay 120 is deenergized by the opening of contactor 101. The car is thus stopped at station II with contactor 28 closed and relay 110 energized, but with the remaining relays in the system open.

With the system in this condition, if a call were placed at station I by a momentary depression of switch 11, it would set up a holding circuit in relay 170 through lower limit switch 17, resulting in energization of relays 140, 90 and 50, and, through the latter, downward-drive operation of the motor, bringing the car to station I. If instead a call were placed at station III through switch 33, it would result in energization of relays 160, 150, 80 and 60, and the car would be brought upward to station III. If two such orders were placed in succession, the first call order to be signalled would be obeyed in the manner just described and then the other would be obeyed after closure of contactor 71 and switches 9, 19, 29 and 39.

If a send order were signalled at station II when the car was at this station, as through a momentary depression of switch 23, this order would prevail over any competing order, e. g. over a call signalled through switch 11 prior to the depression of switch 23. Whereas the call signalled through switch 11 would have set up a holding circuit in relay 170, and, through contactors 186, 171 and 172, would have established energization of relays 140 and 90 and would have established a positive supply circuit up to the coil of relay 50, the depression of send switch 23 would institute the energization of relay 180, opening contactor 186, deenergizing relays 140 and 90, and postponing the downward traction of the car in response to the order signalled through switch 11. Note, however, that the holding circuit through contactor 171 would remain intact. The system operation in response to a send order signalled from intermediate station II is just the

same as in response to a send order from one terminal station to the other, in that one of the priority relays 188, 190 is operated, causing operation in turn of the associated terminal-call holding relay and motor control relay. Thus, the operation in response to the order signalled through switch 23 would correspond to that described above as resulting from a send order signalled through switch 13 when the car was at station I.

The feature of response of the system to a plurality of calls, not necessarily in the time order in which they were signalled but instead in the physical order of the stations to which the car is called with respect to the direction of progress of the car, is illustrated by assuming the car en route downward to station II from station III, and supposing that a call is placed through switch 33 and then a call is placed through switch 11. The car being above station II, contactor 27 is closed and relay 100 is energized. Energization of relay 120, having been previously instituted by current momentarily provided through its coil, e. g. through switch 22, conductors 231 and 295, contactor 182 and conductor 297, is sustained by a holding circuit through contactor 101, conductor 285 and contactor 125. Relays 90 and 50 are energized, the former through contactors 187, 188, 193, 124 and 81, and the latter through contactors 187, 197, 193, 123 and 82. The energization circuits of relays 120, 90 and 50 all are now dependent upon paths through contactors of relay 100; and hence, upon the car reaching station II and throwing switch 23 to the opposite throw position, the operation of the car will be interrupted.

Now, during the downward movement of the car toward station II, suppose an operator at station III momentarily depresses switch 33 to call the car. This actuates relay 160, setting up a holding circuit therein through contactor 161 and limit switch 37. Through contactors 196 and 162 and 131, relay 150 is energized, and conductor 241 is brought to the positive supply potential through contactors 151 and 132. This does not result in immediate energization of relay 60, however, since relay 90 is energized and has contactor 92 open specifically for blocking such premature energization of relay 60.

Through contactors 196 and 163, conductor 271 is brought to the positive supply potential, but open contactor 91 prevents this condition from resulting in an immediate energization of relay 80 and consequent premature interruption of the downward movement of the car.

If no further order were signalled, the car would be made to proceed to station II and stop there, and after the predetermined time interval had elapsed, it would be made to go back up to station III. Assuming, however, that a station I call was signalled through switch 11 after the station III call signal and before the car reached station II, relay 170 would be momentarily energized, establishing its holding circuit through contactor 173 and limit switch 17, and providing an alternative path through conductor 209, contactor 186, conductor 211, and contactor 172 and conductor 215 for retaining direction supervising relay 90 energized after the interruption of the energization path through contactors 187, 197, 193, and 124 upon the car reaching station II and opening the circuits of relay 100.

This circuit established through holding relay 170 is such as to take precedence over the circuits through relay 160, since it is able to retain down-

direction control through the continuation of the energization of relay 90. However, it is not able to establish an alternative supply circuit for relay 50 immediately—if it were permitted to do so, it would cause the car to pass by station II without stopping, and this would violate an objective of the system. Holding relay 170 can provide for the energization of relay 50 only through an intermediate relay, viz. through the energization of relay 140. The current path required for the energization of relay 140 is traced through contactors 173, 186, 171 and 121, the last-named contactor being held open so long as relay 120 is energized.

When the car reaches station II, it transfers the arms of switch 36 to the positions with contactor 27 open and contactor 28 closed. This deenergizes relay 100, and the deenergization of relay 100 in turn causes the simultaneous deenergizations of relays 120 and 50. Almost instantaneously upon these simultaneous deenergizations, contactor 53 opens, so that energization of a motor relay cannot now be reinstated until the predetermined time for the reclosing of contactor 71 has expired. An instant later, the armature of relay 120 reaches its reclosed position, with contactor 121 now closed, and through this contactor relay 140 is thereupon energized. Now, contactor 141 being closed, a path is provided through this contactor, contactor 122 and conductor 227 and contactor 82 for restoring the upper end of the coil of relay 50 to the positive supply potential, so that the relay 50 will again be operated to provide further downward car movement when contactor 71 and switches 9, 19, 29 and 39 are again closed.

The purpose of relay 141 is apparent in the foregoing explanation of the sequence of events occurring with the system responding to a down call to station II when a further down call is signalled in for bringing the car to station I. Relay 170 must hold this further order, but without the completion of the circuit down to the motor control relay, and the latter circuit must not be completed until the motor control relay 50 has been deenergized momentarily to permit contactor 53 to be momentarily opened. This very brief delay in reenergization of the motor control relay is assured by the activation time of relay 140.

The operation and purpose of relay 150, in relation to a station III call order signalled during progress of the car from station I to station II, and in circuit relations with relays 160 and 60 corresponds in all material respects with that described above in connection with relay 140.

The station III call, which in the assumed set of operating conditions was taken to have been signalled through switch 33 before the station I order was signalled through switch 11, though postponed from taking effect after arrival of the car at station II in view of the fact that a further down call order was signalled in while the car descended toward station II, is retained throughout the time of the downward movements of the car, relay 160 remaining energized in its holding circuit throughout this time, and relay 150 being energized through contactor 162 and conductor 299. Upon arrival of the car at station I, the opening of limit switch 17 opens the holding circuit of relay 170, and the energization of relays 90, 50 and 140 is stopped.

With the deenergization of relay 90, contactor 91 is reclosed, so that relay 80 is energized, and contactor 92 is also reclosed so that the upper

end of the coil of relay 60 is brought to the positive supply potential. Then, when contactor 71 and switches 9, 19, 29 and 39 are all closed, the car will be made to proceed upward to station III by the energization of relay 60, this upward movement to be halted only by the attainment of the station III position and the opening of the upper limit switch 37, unless a station II call is signalled to the car before it has passed by station II. Such an intervening order signal would be obeyed by a halt of the car en route to station III, in keeping with the plan of the system to respond to calls not necessarily in the order signalled, but in the order of reaching the calling station in the direction of progress.

From the foregoing description of the dumb-waiter system illustrated in Fig. 2, and from the several examples given of signalling situations which may be encountered therewith and the manners in which the system responds to them, it will be understood that at each station, a car calling button is provided, operable at any time, but incapable of exercising any super-control on the system. A call through such a switch will be answered after all send orders have been fulfilled and when the car has arrived at each preceding station to which it has been called, in the order determined by its direction of movement. Also, at each station is provided one button switch for sending the car to each of the other stations served by the system. A car-operated switch is provided at each station in series with these send-order switches, to prevent mischievous or inadvertent "sending" from a station other than that at which the car is located at the time the operator works the signal buttons.

An operator at the station at which the car is located can employ either of the send buttons located there to send the car to any selected one of the other stations, and in doing so, compels the car to proceed immediately to such selected station irrespective of any other calls already in the system or signalled while the car is en route in obedience to the send order.

In Figs. 3 and 4-A and 4-B is illustrated a multi-station dumbwaiter system generally like that of Figs. 1 and 2, but with four stations.

The control system of Figs. 3, 4-A and 4-B is arranged generally along the lines of the control systems of Figs. 1 and 2, but is different therefrom in the following respects:

- (1) It illustrates the way in which the features of the present invention are applied to an installation serving a plurality of intermediate stations;
- (2) It shows how a bank of control switches may be provided in the car for selective express control thereof; and
- (3) It illustrates the provision of an emergency car-calling switch at each station in addition to the regular no-priority call switches 11, 22, 33 and 44 provided at the respective stations.

Relays 50, 60, 70, 80, 90, 100, 110, 140, 150, 160 and 170 are employed in Figs. 4-A and 4-B just as in Fig. 2. Similarly, lower and upper limit switches 17 and 37 are provided at the lowermost station and the uppermost station, and the double-throw switch 26 is retained at intermediate station II. Relays 120 and 130 of Fig. 2 are replaced by relays 320 and 330 having an additional contactor on each; and the second intermediate station, station III, is provided with 75 a double-throw switch 316 and six relays, 300,

310, 360, 370, 340 and 350 corresponding to switch 26 and relays 100, 110, 320, 330, 149 and 150, respectively, at station II.

The two priority relays 100 and 100 of Fig. 2 for express handling of the car to the terminal stations are replaced by terminal station priority relays 410 and 440 having larger numbers of contacts, and two additional priority relays 420 and 430 are added. Relays 410, 420, 430 and 440 handle priority operations directing the car to stations I, 10 II, III and IV, respectively.

Car cam operated switches 16 and 36 are provided as before at the terminal stations, and switches 19 and 38 have been added at the terminal stations I and IV, respectively, arranged to be normally closed but to be opened by engagement of car cam 6 ahead of switches 16 and 36, respectively.

The station signal switches 11-14, 21-24, 31-34 and added switches 41-44 are each designated, as before, by a first digit denoting the station at which the switch is located and a second digit denoting the station to which it orders the car to travel. As before, cam-operated switches 15, 25 and 35, and newly added switch 45 are arranged to prevent priority "send" orders being placed from a station when the car is not positioned at the send-switch station.

Emergency calling switches 401, 402, 403 and 404 are shown added at the respective stations in Figs. 4-A and 4-B, and moreover, a set of control switches is shown provided in the car, one no-priority switch and one priority switch for directing the car to each of the stations. It will be appreciated that a three-stop system such as shown in Fig. 2 may readily be provided with emergency call switches such as 401, 402 and 403 and with car switches such as 451, 452, 453, 461, 462 and 463, neither of these features being limited in any way to a four-station system.

As with the system of Figs. 1 and 2, the 4-station arrangement of Figs. 3, 4-A and 4-B does not require the benefit of the priority relay features for those orders directing the car from a terminal station to the adjacent intermediate station, i. e. from station I to station II or from station IV to station III, but the priority relays are used for all other send orders as well as for emergency call orders placeable through emergency switches 401, 402, 403 and 404.

The double bank of switches 450 in the car is a feature making possible the use of this control system for elevator purposes as well as for a mere cargo conveying system of the dumbwaiter type. Moreover, with express sending switches 451, 452, 453 and 454 in the car, the sending switches at the stations, such as switches 12, 13 and 14 at station I may be eliminated if desired. Thus four priority send switches 451, 452, 453 and 454 in the car may be used in a 4-station system to replace twelve fixedly mounted send switches, such as switches 12, 13 and 14 at station I and switches 21, 23 and 24 at station II. Obviously, a send order can only be placed through the switches in bank 450 by an operator at the station at which the car is then positioned, considering the system as applied to a dumbwaiter, since anyone at any other station lacks immediate access to the interior of the car.

The connections of priority relays 440 and 440 correspond most closely with those of the priority relays 100 and 100, respectively, of Fig. 2, the differences being merely addition of further contacts to provide for the required interconnections with relays 420 and 430.

The important features of performance of the 75

system of Figs. 3, 4-A and 4-B according to the principles of answering regular (no-priority) calls in the turn corresponding to the physical order of the call stations taking into account the direction of travel of the car, storing all calls so long as they remain unanswered, and providing for superseding or by-pass or priority operation where the car is being sent for one station to another, are set forth by discussion of the operation of the system in response to a variety of signals. Suppose that the car is at station IV, and a station I call signal is placed through switch 11. Continuing, suppose that the car is proceeding downward in response to this call, between station III and station II, when two further calls are placed in close succession, a station III call through switch 33, and then a station II call through switch 22. The station III call will not interrupt the downward movement of the car, 15 but the station II call will halt the car in its downward trip.

Still further, suppose that after resumption of the downward travel from station II, an emergency call to station IV is signalled through switch 404, and suppose that the operator at this station, upon gaining access to the car, loads it with material urgently needed at station II, and presses either switch 42 or switch 452 to send the car non-stop to station II. Assuming 20 that no further orders are placed, the car, after proceeding directly to station II in compliance with the send order, will then go on to station I, and finally it will go to station III. The way in which the system is made to accommodate such a 25 variety of signals and to provide full eventual compliance with all of the signals, will now be explained in detail.

With the depression of switch 11, the coil of relay 170 is momentarily energized through the 40 circuit including switch 11, conductor 471, and lower limit switch 17. The holding circuit is thereupon established through contactor 173, retaining relay 170 closed. Relays 410, 420, 430 and 440 are all deenergized. The circuit from the positive (lower) terminal of the coil of relay 170 is extended through conductor 473, contactors 4291, 430 and 4492 and conductor 475 to contactors 171 and 172. Through contactor 172, the positive supply voltage is carried through conductor 477 and through contactor 31 to the coil of relay 90, energizing relay 90 and making possible a circuit for relay 50. Through contactor 171, the circuit is extended through conductor 479 to contactor 322, through which the coil of relay 140 is energized. Now through conductor 481 and contactor 141, the positive supply circuit is further extended through contactor 321 and conductor 483 to contactor 362, and through this contactor to the coil of relay 340. Through conductor 485, contactors 341 and 361 and conductor 487, the positive supply circuit is then extended to contactor 92 and through this contactor to the coil of the down-direction motor operation relay 52, energizing this relay and thus causing the motor to operate to drive the car downward.

If no further order were signalled during the descent of the car, it would be driven continuously down to station I, the circuits including relays 170, 140, 340, 90 and 50 remaining intact until arrival of the car at the lowermost station, at which cam 6 would open switch 17 to interrupt the holding circuit of relay 170 and cause relays 140, 340, 90 and 50 to be deenergized as a consequence, stopping the motor.

However, continuing with the above assumed

illustrative conditions, switch 33 is operated while the car is descending between station III and station II. The momentary depression of switch 33 carries the positive supply voltage over conductors 491 and 512 to contactors 301 and 311. The car having passed beyond (below) station III, switch 316 is in the throw with contactor 317 open and contactor 318 closed, so that relay 310 is energized and contactors 311, 312 and 313 are closed. Conversely, contactors 301, 302 and 303 are open at this time. Therefore, the circuit through conductors 491 and 512 is continued through contactor 311 and conductor 493 to the coil of relay 370, which accordingly is energized. It is to be noted, however, that this energization of relay 370, resulting in establishment of a holding circuit through conductor 495 and contactors 312 and 375, does not affect any of the circuits which are active in causing the descent of the car, so that the motor continues to drive the car unchecked toward station I.

Going still further in accordance with the assumed set of signals, switch 22 is depressed momentarily while the car is yet in transit between station III and station II. This brings conductor 497 to the positive supply potential, and accordingly applies this potential to contactors 101 and 111. The car being above station II, contactor 27 is closed and contactor 28 is yet open, so that contactors 101, 102 and 103 are closed and contactors 111, 112 and 113 are open. Accordingly, the coil of relay 320 is momentarily energized through contactor 101 and conductor 499, and the holding circuit for retaining this relay energized is established through conductor 501 and contactors 102 and 325. With the energization of relay 320, contactors 321 and 322 are opened, causing deenergization of relay 140, but conductor 483 is held at the positive supply potential through contactors 445, 433 and 415, conductor 503, contactor 103, conductor 505, and contactor 323. An alternative path for the positive supply potential existent as a result of the continued holding condition of relay 170, is traced through conductor 477, conductor 507, and contactors 324 and 323.

When the car reaches station II, it transfers the arms of switch 26 to neutral, opening contactor 27. With the opening of contactor 27, contactors 101, 102 and 103 are opened, and the supply circuit of relay 320 is broken. This causes the opening of contactors 323 and 324, interrupting the positive potential supply circuit of conductor 483, contactor 362, and relay 340, and hence opening the supply circuit of relay 50. In the time interval required for the reclosing of contactors 321 and 322 and the reenergization of relay 140, and the ensuing reenergization of relay 340 through the circuits maintained through contactors 171 and 172 by the continued holding of relay 170, ample time is provided for the armature of relay 50 to drop to its idle position, so that contactor 53 is opened and the supply circuit of relay 50 is rendered incapable of being reclosed until the predetermined delay time interval assured by mechanism 72. Thus, the car is stopped at station II in response to the signal given through switch 22, prior to its continuance downward to respond to the original call through switch 11. Direction control relay 90 remains energized all this while through contactor 172, conductor 477, and contactor 81, blocking relays 80 and 60.

When the predetermined delay time has elapsed and contactor 71 is reclosed, and switches 9 and 75

29 both are closed, the circuit maintained through contactors 171 and 172 by the continued holding of relay 170 again provides for energization of relay 50 through the path formerly traced through conductor 479, contactor 322, relay 140, conductor 483, relay 340 and conductor 481, so that the car is made to resume its downward journey toward station I.

According to the fourth of the assumed signalling operations, emergency call switch 404 is momentarily depressed while the car is en route from station II to station I. Through this switch, conductor 511 is brought to the positive supply potential, and through switch 38, conductor 513 is similarly brought to this voltage. A circuit is now established thence through conductor 515 and contactors 434, 424 and 416 for the momentary energization of priority control relay 440. With this momentary energization of relay 440, contactor 441 is closed, energizing relay 160 momentarily so that a holding circuit therefor is established through contactor 161 and upper limit switch 37. Through contactors 411, 421 and 4391, and thence through contactors 162 and 163, three conductors 523, 525 and 531 are all brought to the positive supply potential. Through conductor 531 and contactor 446, the circuit for energization of relay 440 through contactors 434, 424 and 416 is held complete, holding relay 440 energized until the car shall arrive at station IV and open switch 37.

At the energization of relay 440, the opening of contactor 4492 breaks all circuits through relay 170 except its holding circuit through contactor 173. Therefore, the positive potential supply to conductors 477 and 479 is broken, and relays 140, 360, 50 and 90 are deenergized. With the deenergization of relay 90, contactor 91 recloses, and now down-direction blocking relay 80 is energized. The opening of contactors 447, 448 and 449 prevents energization of any of the other priority relays so long as relay 440 is held energized.

Through contactor 4491, conductor 527 and newly closed contactor 82, up-direction motor supply relay 60 is energized as soon as the delay period of mechanism 72 has passed, starting the car on its ascent toward station IV.

The opening of contactors 444 and 445 prevents the energization of any circuits through any of contactors 163, 113, 303 and 313 so long as relay 440 remains energized.

The closure of contactors 442 and 443 places conductors 561 and 563 at the positive supply potential. Conductor 561 leads to contactors 366 and 377, and conductor 563 leads to contactors 326 and 331. Relay 370 being held energized through the circuit including contactors 312 and 375, contactor 377 is closed, and therefore relay 360 is now energized through contactors 443 and 442, conductor 561 and contactor 377.

The energization circuit of relay 60 being completed directly through relays 440 and 160 and being independent of relay 360, the car will not be stopped at station III, but will continue past this station to station IV. As it passes station III, cam 6 nevertheless engages switch 316 and throws it to the position with contactor 318 open and contactor 317 closed, so that relay 300 is energized and relays 310 and 370 are deenergized. Now, with the car above station III, the up-direction car call holding condition, until now maintained in relay 370, has been discarded and replaced by a down-direction car call holding condition in relay 360.

With the conditions as just described, the car

has been halted in its descent between station II and station I, has been delayed at an intermediate position in the hatchway for the brief interval for which mechanism 72 is preset, and has thereupon been lifted directly to station IV; and while this process was being carried out, the unanswered call to station I has been held stored in relay 170, and the unanswered call to station III, formerly held in relay 370 to bring the car up to the station, has been retained as a down-call held in relay 360.

The car is of course halted at terminal station IV at the opening of switch 31, and it is retained at this station for the delay period assured by delay relay 10. If the emergency call to station IV is merely an emergency recall to extract from the car something which should earlier have been taken therefrom, and if no send order were placed in the system by the operator at station IV, then the station III call could next be answered by the car, and thereafter it would proceed to station I. However, in the assumed set of circumstances, a fifth signalling operation involved the momentary depression of switch 42 by the operator at station IV who had made the emergency call. Such a signalling operation is available to him for the purpose of sending the car directly to a destination of his choice, e. g. station II, regardless of the other calls such as those of station III and station I remaining stored in the system.

With the depression of switch 42 while the car is at station IV and cam 5 holds switch 45 closed (the depression of switch 452 in the car would yield just the same result) conductor 541 is brought to the positive supply potential, and through this conductor and contactors 431, 449 and 419, relay 420 is momentarily energized. During this momentary energization, contactor 422 brings conductor 543 to the positive supply potential; energizing relay 370 through contactor 367, and contactor 420 brings conductor 497 to the positive supply potential. Through the latter conductor, a circuit is completed through one of contactors 101 and 111; in the present instance, the car being above station II, contactor 21 is closed and relay 100 is energized, so that contactor 101 is closed and down call holding relay 320 is momentarily energized therethrough. The holding circuit for relay 320 is completed through contactor 102 and contactor 325. Through contactors 445, 433 and 415, conductor 503, contactor 103, conductor 505 and contactor 324, the previously described circuits are energized for maintaining coil 90 energized.

The circuit for holding relay 420 energized is now traced from conductor 505 through contactors 323, 329 conductor 615, contactors 427, 431, 449 and 419 to the coil of relay 420. Another circuit is traced through contactors 427 and 428, conductor 617, contactor 328, to conductor 487, through contactor 92 to the coil of relay 50, for downward motor propulsion of the car.

With the operation of double-throw switch 26, relay 100 is deenergized and relay 320 is in turn deenergized, and the holding circuit for relay 420 also is broken. Thus the car has been brought to station II and stopped there, and the holding circuits including relay 420 for bringing it directly to this station have been erased.

There remain to be fulfilled the calls held for stations I and III. The call to station I will be answered first since the operation of the car in the last phase was in the downward direction,

away from station III and toward station I, and updirection blocking relay 90 is continued in its energized condition through contactors 173, 4211, 439, 4492, 172 and 31. When the use of the car at station II has been completed and switches 9 and 29 are closed and contactor 71 is reclosed, the circuits held through relay 170 and contactors 4211, 439 and 4492 are once more effective through operation of relays 90, 140 and 340 to cause the energization of relay 50 and the consequent downward drive of the motor bringing the car to station I, where these circuits are all broken through the opening of the lower limit switch 17, and relay 80 is energized to insure that relay 90 will remain open and that the next operation of the car will be an ascent instituted through relay 60.

Now, at station III, contactor 317 is open and contactor 318 is closed, and relay 319 is energized with contactors 311, 312 and 313 closed as a result. Relay 370 is now also held energized through the circuit including conductor 495, contactor 312 and contactor 375. Upon completion of the use of the car at station I, and with switches 9 and 19 closed and contactor 71 reclosed following the time interval for which mechanism 72 is preadjusted, the positive supply circuit for relay 60 is established through contactors 444, 423 and 414, conductor 571, conductor 573, contactor 313, conductor 575, contactor 373, conductor 577, contactor 332 (with consequent energization of relay 150), contactors 151 and 331, conductor 579 and contactor 82 to the coil of relay 60.

This provides for the upward drive of the car, and these circuits remain unchanged until the car reaches station III. Car cam 6 there transfers the arms of switch 316 to open contactor 318, opening the circuits of relay 319 and relay 370 in turn, and breaking the supply circuit of relay 60 to arrest the operation of the car drive motor with the car at station III. The system is now left in readiness for any further use, and any further uses thereof will be carried out in accordance with the general principles which are illustrated with the foregoing examples.

While the fixed-station send switches located at the respective terminals for sending the car to the respective next stations, as switch 43 for sending the car from station IV to station III or switch 12 for sending the car from station I to station II, are shown connected to operate directly upon the intermediate station call holding circuits 360 and 330, without reliance upon the priority-assurance relays 439 and 420, respectively, such send switches could be connected for operation through the priority relays if desired. When the car is at a terminal station, it is necessary that the direction of next operation must be to the next station, but it is possible that an emergency call signal or a signal placed in the car if used for elevator purposes may override the send order placed through switch 43 or switch 12, connected as shown, and cause the car to by-pass this station.

In any event, the express switches 452 and 453 in the car must be connected for operation through the express relays 420 and 430, since these switches must operate properly regardless of the location of the car at the time of signalling an order through one of these switches. If the car is at station I and it is desired that it be sent directly and immediately to station II by a signal placed in the car, the appropriate switch 452 is momentarily depressed. Through conduc-

tor 541, the contactors 437, 449 and 419, the coil of relay 420 is momentarily energized. Then, through contactor 429, conductor 497, contactor 111 (closed because the car is beneath station II and relay 110 is energized through contactor 28), relay 330 is energized, and a holding circuit therefor is provided through contactors 112 and 335.

A positive-supply energization circuit is now traceable through contactors 445, 433, and 415, conductor 503, contactor 113, and contactor 334, to conductor 523. Through the latter, down-direction blocking relay 80 is energized.

Another circuit is established through contactors 445, 433, 415, conductor 503, and contactor 113 to contactor 333. From contactor 333, one circuit continues to the coil of relay 60, through conductor 579 and contactor 82, providing for upward propulsion. From contactor 333 another circuit is traced through contactor 339, conductor 615, through contactors 427, 437, 449 and 419 to the coil of relay 420, holding this relay energized.

Yet a further circuit is established from contactor 333 through contactor 339, via conductor 615, through contactors 427 and 428, through conductor 617, contactors 338 and 82 to the coil of relay 60, an alternative circuit available for directional control where more than two intermediate stations are provided.

The above-described holding circuit for relay 420 will be retained energized until the car arrives at station II and opens contactor 28, causing relay 110 to be de-energized, in turn opening the holding circuit of relay 330, and consequently opening the holding circuit of relay 420. For this type of operation of the car, the important function of relay 420 is to block the energization of any other of the priority control relays 410, 430 and 440 through the opening of contactors 425, 426 and 424, respectively.

As mentioned above, such operation through the intermediate station priority relays 420, 430 may be provided in connection with switches 12 and 43, these switches being connected in shunt with switches 452 and 453 for this purpose and producing operation in the manner just described, instead of their connections in parallel with switches 22 and 33, respectively, as shown in the drawings.

No details of the car propelling system have been shown in the drawings, as any of the well known car hoisting and lowering systems can be used, as for example, an electric motor system or an hydraulic system. Thus, the motor control relays 50 and 60 shown in the various embodiments of the invention may be employed to control the directional power circuits of a reversible alternating current motor or those of a reversible direct current motor, or they may be employed to control the operating valves of a hydraulic car motivating arrangement, for example.

A feature of the present invention of great importance is the freedom from interference of the express or priority control arrangements with call holding circuits for stations other than the station to which the car is directed under priority control. With this feature, calls signalled before or during the priority operation are retained held for subsequent response, except for a call to the station to which the car is directed by priority operation. Such a call as this is of course cancelled upon arrival of the car at the calling station.

To illustrate an extreme case, an operator at the station at which the car is located can "call" 75

the car and also place a send order to direct the car to another station, and the "call" order, whether placed before or after the send order or exactly simultaneously therewith, is given full effect, in that a non-priority car recall circuit is established, to remain intact until it has eventually returned the car to the station whence it was originally sent.

Where in the specification and claims reference is made to positioning of switches in the hatchway and operation thereof by cams upon the car, it will be appreciated that such operation may be achieved remotely from the hatchway, as in miniature geared-down and coupled relatively movable parts. As one example, a miniature dummy car may be coupled to the main car 1 for scaled-down movements along an appropriately scaled hatchway, oriented vertically or otherwise as desired, and the cams and control switches may be associated therewith to provide for greater compactness of the control circuits. Similarly, a coupled control unit bearing cams corresponding to cams 5 and 6 may be made angularly movable, if desired, with control switches placed at appropriate angles about the axis of rotation, and with suitable gearing to the car suspension system to insure the positive maintenance of the desired relations between linear car movement and the angular movement of the cam bearing unit.

Moreover, the cams 5 and 6 may be replaced if desired by units obviating physical contact with the hatchway control switches, as by photoelectric, magnetic or capacitive operating arrangements of well-known types.

In the systems of Figs. 1-2 and Figs. 3-4, the cam-operated switches connected between the positive supply conductor and the send switches at the terminal stations are fully effective to guard against an operator at a terminal station placing "send" orders mischievously when the car is elsewhere. The similar cam-operated switches at the intermediate stations are similarly effective under most conditions, but an operator at one of the intermediate stations, bent on mischief, can depress a send order switch and hold it closed while the car passes the station, and in this way establish a "send" order holding circuit which can make the car stop before reaching its destination and go to a different station on an entirely wasteful errand.

One way to avoid this difficulty, where the system is used only as a dumbwaiter, is to arrange the send signal blocking switches at the intermediate stations, such as switch 25 at station II, to be operated by the sliding door at the respective station, or by the guard gate which may be included on the dumbwaiter car for protection against interference of any of the material transported therein from projecting against the hatchway wall. Another way to avoid this remote possibility of trouble with the system due to mischief is to replace fixed cam 5 with a "retiring cam"—a cam electromagnetically operated and arranged for projection from the car only when the car is at a station.

A "retiring cam" arrangement is illustrated in Fig. 5 at 5', the cam element being supported on the plunger of a solenoid and being sprung urged into the position of projection from a suitable recess provided in the side wall of the car. The coil 5'' is connected between the positive supply end (lower end) of the coil of relay 10 and the negative supply main, so that the coil 5'' is energized and cam 5' is retracted into its recess

whenever either relay 50 or relay 60 is energized, and thus whenever the car is moved. With this method of connection of the retiring cam, it is easily fitted into a system according to the present invention, irrespective of the number of intermediate stations the system is arranged to serve. It will be readily apparent that the coil 5" need not necessarily be connected to the coil of relay 70, and that the coil 5" may be connected to an additional set of contactors on relays 50 and 60 if preferred.

Since many changes could be made in the above construction and many apparently widely different embodiments of this invention could be made without departing from the scope thereof, it is intended that all the matter contained in the above description and shown in the accompanying drawings shall be interpreted as illustrative and not in a limiting sense.

What is claimed is:

1. A control system for a vertical lift apparatus of the type including a hatchway extending between an upper terminal station and a lower terminal station with at least one intermediate station and with a car guided in said hatchway and motor propelled for upward and downward movement therein, the control system comprising: means at each of said stations for signalling calls to bring the car thereto, means for receiving said calls and holding them until fulfilled by a stop of the car at the station, directional order control means for causing the car to proceed in the direction of progress corresponding to its last direction of movement until it has made a stop for every one of the calls therebeyond in the last direction of movement and for then causing the car to proceed to answer any calls to stations in the opposite direction therefrom, means for signalling an order to send the car from a station at which it is positioned to a selected station destination, means for receiving and holding said send order until said car has stopped at said destination, and means responsive thereto for postponing response of said car to any call signals until it has stopped at said destination.

2. A control system for a vertical lift apparatus of the type including a hatchway extending between an upper terminal station and a lower terminal station with at least one intermediate station and with a car guided in said hatchway and motor propelled for upward and downward movement therein, the control system comprising: means at each of said stations for signalling calls to bring the car thereto, means for receiving said calls and holding them until fulfilled by a stop of the car at the station, directional order control means for causing the car to proceed in the direction of progress corresponding to its last direction of movement until it has made a stop for every one of the calls therebeyond in the last direction of movement and for then causing the car to proceed to answer any calls to stations in the opposite direction therefrom, means for signalling an order to send the car directly from a station at which it is positioned to a selected station destination, means for receiving and holding said send order until said car has stopped at said destination and for rendering said directional order control means inoperative until said car has stopped at said destination, and means operative upon the arrival of said car at said destination for reinstating operation of said car in response to calls in accordance with said directional order control means.

3. A control system as defined in claim 1, wherein: said means for signalling calls comprise a call switch at the upper terminal station, a call switch at the lower terminal station, and a call switch at each intermediate station; said call receiving and holding means comprise a holding relay coupled to said upper terminal station call switch, a holding relay coupled to said lower terminal station call switch and means for holding a call circuit for each intermediate station for the direction in which the car must come thereto, each of said holding relays including a contactor for actuation of the motor control circuits; said means for receiving and holding said send order comprises a holding relay responsive to said send order signalling means; and said means responsive thereto for postponing response of said car comprises contactor means on said send order responsive holding relay for blocking the circuits of said contactors on said call holding relays.

4. A control system as defined in claim 2 wherein: said directional order control means comprises a down direction control circuit blocking relay and an up direction control circuit blocking relay, each relay including a normally closed contactor in series with the actuation circuit of the other whereby either relay, upon actuation, blocks the energization of the other so long as the first remains actuated; the control system including connections between the actuation circuit of the up direction blocking relay and the down direction holding relays for the intermediate and lower terminal stations, and connections between the actuation circuit of the down direction blocking relay and the up direction holding relays for the intermediate and upper terminal stations.

5. A control system for a vertical lift apparatus of the type including a hatchway extending between an upper terminal station and a lower terminal station with at least one intermediate station and with a car guided in said hatchway and motor propelled for upward and downward movement therein, the control system comprising: means at each of said stations for signalling calls to bring the car thereto, means for receiving said calls and holding each call until fulfilled by a stop of the car at the call station, directional order control means for causing the car to proceed in one direction and stop at each call station reached in that direction until no further calling stations lie ahead, means for holding the car at each station at which it stops for a predetermined minimum period, means for signalling an order to send the car from a station at which it is positioned to any selected station destination, means for receiving and holding said send order until said car has stopped at said destination, and means responsive thereto for postponing response of said car to any call signals until it has stopped at said destination.

6. A control system as defined in claim 5, wherein said means for holding the car at each station at which it stops for a predetermined minimum period comprises a time delay relay connected to be energized concurrently with the car propelling motor and including normally closed contactor means for blocking the establishment of a motor actuating circuit until the delay relay has reclosed, said delay relay also including a reclosing delay mechanism for holding said contactor open a predetermined period of time after cessation of energization of said delay relay.

7. A control system for a vertical lift apparatus of the type including a hatchway extending between an upper terminal station and a lower terminal station with at least one intermediate station and with a car guided in said hatchway and motor propelled for upward and downward movement therein, the control system comprising: means at each of said stations for signalling calls to bring the car thereto, means for receiving and holding each call until fulfilled by a stop of the car at the call station, directional order control means for causing the car to proceed in one direction and stop at each call station reached in that direction until no further call station lies ahead in that direction, means for holding the car at each station at which it is stopped for a predetermined minimum waiting period, means for signalling an order to send the car from a station at which it is positioned to any selected station destination, means for receiving and holding said send order until the car has arrived at said destination, means responsive thereto for postponing response of said car to call signals until it has arrived at said destination, and emergency call signalling means coupled to said send order receiving and holding means to provide for priority calls to be given immediate and direct response ahead of ordinary calls.

8. A control system for a vertical lift apparatus of the type including a hatchway extending between an upper terminal station and a lower terminal station with at least one intermediate station and with a car guided in said hatchway and motor propelled for upward and downward movement therein, the control system comprising: means at each of said stations for signalling calls to bring the car thereto, means for receiving and holding each call until fulfilled by a stop of the car at the call station, directional order control means for causing the car to proceed in one direction and stop at each call station reached in that direction until no further call station lies ahead in that direction, means for holding the car at each station at which it is stopped for a predetermined minimum waiting period, means for signalling an order to send the car from a station at which it is positioned to any selected station destination, means for receiving and holding said send order until the car has arrived at said destination, and means responsive thereto for postponing response of said car to call signals until it has arrived at said destination, said means for signalling an order to send the car comprising at least one signalling switch at each of a plurality of stations, and means blocking circuit actuation through all send order signalling switches other than those at a station at which the car is positioned.

9. A control system as defined in claim 8, wherein in said means blocking circuit actuation comprises a normally open cam switch at each station in series with the send switches thereat, and cam means on the car for closing said cam switch when the car arrives at the station.

10. A control system as defined in claim 9, wherein the cam means on the car comprises a retiring cam, and means positioning said retiring cam for actuation of the series switch at a station when the car is stopped at the station, but keeping the cam retired or retracted when the car is in transit.

11. A control system for a vertical lift apparatus of the type including a hatchway extending between an upper terminal station and a lower ter-

75 minal station with at least one intermediate station and with a car guided in said hatchway and motor propelled for upward and downward movement therein, the control system comprising: means at each of said stations for signalling calls to bring the car thereto, means for receiving and holding each call until fulfilled by a stop of the car at the call station, directional order control means for causing the car to proceed in one direction and stop at each call station reached in that direction until no further call station lies ahead in that direction, means for holding the car at each station at which it is stopped for a predetermined minimum waiting period, means 10 including send order signalling switches in the car for signalling an order to send the car from a station at which it is positioned to any selected station destination, means for receiving and holding said send order until the car has arrived at said destination, and means responsive thereto for postponing response of said car to call signals until it has arrived at said destination.

12. A control system for a vertical lift apparatus as defined in claim 11, further including at 25 least one additional switch in the car for registering a non-priority sending order to set up a holding circuit corresponding to a call signal for the floor to which said additional switch is to direct the car.

13. A control system for a vertical lift apparatus of the type including a hatchway extending between an uppermost station and a lowermost station with at least one intermediate station and with a car guided in said hatchway and motor propelled for upward and downward movement therein, the control system comprising: means at each of said stations for signalling a call to bring the car thereto, means for receiving and holding each call until fulfilled by a stop of the car at the call station, directional order control means for causing the car to proceed in one direction and stop at each call station reached in that direction until no further call station lies ahead in that direction, means for holding the car at each station at which it is stopped for a predetermined minimum waiting period, means 35 including a plurality of send order signalling switches in the car, one for each station destination, for signalling an order to send the car to any selected station destination, means for receiving and holding said send order until the car has arrived at said destination, means responsive thereto for postponing response of said car to call signals until it has arrived at said destination, and means for preventing establishment of any 40 further send order holding circuit for any other destination until the car has arrived at said selected station destination.

14. A control system for a vertical lift apparatus of the type including a hatchway extending between an upper terminal station and a lower terminal station with at least one intermediate station and with a car guided in said hatchway and motor propelled for upward and downward movement therein, the control system comprising: means at each of said stations for signalling a call to bring the car thereto, means associated with each station for receiving and holding a call until fulfilled by a stop of the car at the call station, directional order control means for causing the car to proceed in one direction and stop at each station reached in that direction until no further call station lies ahead in that direction, and thereafter permitting the car to respond to calls in the opposite direction, means for 45 50 55 60 65 70 75

signalling an order to send the car from a station at which it is positioned to a selected station destination, means for receiving and holding said send order until said car has proceeded to and stopped at said destination, and means responsive thereto for postponing response of said car to any call signals until it has stopped at said destination and for causing the car drive motor to propel the car directly to said destination, said last-named means being coupled to the call receiving and holding means for the other stations than said destination to postpone response thereto but permitting calls held in those receiving and holding means to be retained intact and further calls to be signalled effectively during response of the car to the send order.

15. A control system for a vertical lift apparatus of the type including a hatchway extending between an upper terminal station and a lower terminal station with at least one intermediate station and with a car guided in said hatchway and motor propelled for upward and downward movement therein, the control system comprising: means at each of said stations for signalling calls to bring the car thereto, means for receiving said calls and holding them until fulfilled by a stop of the car at the station, directional order control means for causing the car to proceed in the direction of progress corresponding to its last direction of movement until it has made a stop for every one of the calls therebeyond in the last direction of movement and for then causing the car to proceed to answer any calls to stations in the opposite direction therefrom, means including a plurality of send order signalling switches in the car, one for each station destination to which the car may be sent, for signalling an order to send the car to any selected destination, means for receiving and holding said send order until the car has arrived at said destination, means responsive thereto for postponing response of said car to call signals until it has arrived at said destination but leaving intact all calls previously signalled and held except a call for the destination and permitting further effective call signalling during the response to the send order, and means responsive to said send order receiving and holding means for causing the car to be propelled directly to that destination.

16. A control system for a vertical lift apparatus of the type including a hatchway extending between an upper terminal station and a lower terminal station with at least one intermediate station and with a car guided in said hatchway and motor propelled for upward and downward movement therein, the control system comprising: means at each of said stations for signalling calls to bring the car thereto, means for receiving and holding each call until fulfilled by a stop of the car at the call station, directional order control means for causing the car to proceed in one direction and stop at each call station reached in that direction until no further call station lies ahead in that direction, means including a plurality of floor selection switches for signalling an order to send the car directly to a selected station destination, means coupled to each of said floor selection switches for receiving and holding a send order signalled therethrough until the car has arrived at the corresponding station destination, means responsive to a send order for blocking response to all calls until the car has arrived at said corresponding station destination but leaving all calls from stations other than the destination signalled prior to the arrival of the

car at said destination held intact to be answered thereafter, and means responsive to a first signalled send order for blocking the holding of any further send order until the car has arrived at the station destination of the first signalled send order.

17. A control system for a vertical lift apparatus of the type including a hatchway extending between an upper terminal station and a lower terminal station with at least one intermediate station and with a car guided in said hatchway and motor propelled for upward and downward movement therein, the total number of stations being represented as n , the control system comprising: means at each of said n stations for signalling calls to bring the car thereto, means for receiving and holding each call until fulfilled by a stop of the car at the call station, directional order control means for causing the car to proceed in one direction and stop at each call station reached in that direction until no further call station lies ahead in that direction, means including n floor selection switches for signalling orders to send the car directly to a selected station destination, means coupled to each of said floor selection switches for receiving and holding a send order signalled therethrough until the car has arrived at the corresponding station destination, means responsive to a send order for blocking response to all calls until the car has arrived at said corresponding station destination but leaving all calls signalled prior to the arrival of the car at said corresponding station destination held intact to be answered thereafter, means for actuating all means actuatable through the floor selection switch for signalling orders to send the car to said one of the stations, and means for limiting the response of said means coupled to each of said floor selection switches to the first of the send orders and emergency call orders signalled until such first order has been fulfilled.

18. A control system for a vertical lift apparatus as defined in claim 17, wherein said send order receiving and holding means comprises n send order holding relays, one for each station, each send order holding relay having an actuation coil coupled to the send order signalling means for the corresponding station and having a holding circuit contactor connected thereto and having further contactor means for isolating said call receiving and holding means from the motor control circuits and for actuating said control circuits directly until the car has arrived at the destination.

19. A control system for a vertical lift apparatus as defined in claim 18, wherein at least one of said floor selection switches for signalling orders to send the car is located at a station, and means is provided in circuit with this floor selection switch and the actuation coil of the associated send order holding relay for blocking actuation of the relay when the car is in transit or at another station, the emergency call means being directly operably connected with the actuation circuit of the send order holding relay for the emergency call station independently of position or motion of the car.

20. A control system for a vertical lift apparatus of the type including a hatchway extending between an uppermost terminal station and a lowermost terminal station with at least one intermediate station and with a car guided in said hatchway and motor propelled for upward

75

and downward movement therein, the control system comprising: means at each of said terminal stations for signalling calls to bring the car thereto, means coupled to each of said terminal station call signalling means for receiving and holding a call until fulfilled by a stop of the car at the call station, means at each of said intermediate stations for signalling calls to bring the car thereto, means coupled to each of said intermediate station call signalling means for receiving and holding a call until fulfilled by a stop of the car at the intermediate call station, directional order control means for causing the car to proceed in one direction and stop at each call station reached in that direction until no further call station lies ahead in that direction, means including a plurality of floor selection switches for signalling orders to send the car directly to a selected station destination, means coupled to said last-named means for receiving and holding an order signalled therethrough and blocking response to all calls until the car has arrived at the corresponding station destination, and means responsive to an order held in said last-named means for causing the car propelling motor to propel the car directly to said destination, said intermediate station call receiving and holding means comprising means including a car-actuated change-over device for establishing a motor control circuit to bring the car upward thereto if the car is below the intermediate calling station and for establishing a motor control circuit to bring the car downward thereto if the car is above said intermediate calling station, and means for changing an upward intermediate station call to a downward call when the car is sent upward past the intermediate call station and for changing a downward intermediate station call to an upward call when the car is sent downward past the intermediate call station.

21. A control system for a vertical lift apparatus as defined in claim 20, wherein said intermediate station call receiving and holding means comprises an up-direction call holding relay and a down-direction call holding relay, said car-actuated change-over device being a double-throw switch positioned at the intermediate station in the hatchway to be thrown as the car moves past the intermediate station, the double-throw switch rendering the down-direction holding relay subject to actuation when the car has passed above and rendering the up-direction holding relay subject to actuation when the car has passed below the intermediate station.

22. A control system for a vertical lift apparatus as defined in claim 21, wherein a throw of said double-throw switch as the car moves upward thereby interrupts the holding circuit of the up-direction intermediate station call holding relay and a throw of said double-throw switch as the car moves downward thereby interrupts the holding circuit of the down-direction intermediate station call holding relay.

23. A control system for a vertical lift apparatus of the type including a hatchway extending between an upper terminal station and a lower terminal station with at least one intermediate station and with a car guided in said hatchway and motor propelled for upward and downward movement therein, the control system comprising: means at each of said terminal stations for signalling calls to bring the car thereto, means coupled to each of said terminal station call signalling means for receiving and holding a call until fulfilled by a stop of the

car at the terminal call station, means at each intermediate station for signalling calls to bring the car thereto, means for receiving the intermediate station call and holding a circuit for bringing the car upward thereto if it is beneath the calling intermediate station at the time of signalling and for bringing the car downward thereto if it is above the calling intermediate station at the time of signalling, means operable for causing continuous movement of the car past the calling intermediate station, and means coupled to said last-named means for changing a down-call to an up-call as the car descends past the calling intermediate station and changing an up-call to a down-call as the car ascends past the calling intermediate station.

24. A control system for a vertical lift apparatus as defined in claim 23, wherein said intermediate station call receiving and circuit holding means comprises an up-direction call holding relay and a down-direction call holding relay, and means including a double-throw switch arranged at the intermediate station in the hatchway for operation by movement of the car as it passes the station for coupling the intermediate station call signalling means to the holding relay corresponding to the direction in which the car must travel to arrive at the calling intermediate station.

25. A control system for a vertical lift apparatus as defined in claim 24, wherein each of said intermediate station call holding relays includes a normally open contactor, and said changing means comprises means coupling the actuation circuit of each of said relays to the normally open contactor of the other relay, and means coupling said normally open contactors to said continuous movement causing means for establishing energization through one relay of the other relay when the car is propelled in the call direction of the one relay under control of the continuous movement causing means.

26. A control system for a vertical lift apparatus as defined in claim 23, wherein said means operable for causing continuous movement of the car past the calling intermediate station comprises means including at least one controller in the car for establishing a propelling motor control circuit independent of any call holding means and for leaving intact all call holding circuits for stations other than those traversed by the car.

27. A control system for a vertical lift apparatus as defined in claim 23, wherein said means operable for causing continuous movement of the car past the calling intermediate station comprises means including at least one control switch positioned at a station for establishing a propelling motor control circuit independent of any call holding means and for leaving intact all call holding circuits for stations other than those traversed by the car.

28. A control system for a vertical lift apparatus of the type including a hatchway extending between an upper terminal station and a lower terminal station with at least one intermediate station and with a car guided in said hatchway and motor propelled for upward and downward movement therein, the control system comprising: means at each of said terminal stations for signalling calls to bring the car thereto, means coupled to each of said terminal station call signalling means for receiving and holding a call until fulfilled by a stop of the car at the calling terminal station, means at

31

each intermediate station for signalling calls to bring the car thereto, an up-direction intermediate station call holding circuit and a down-direction intermediate call holding circuit for the intermediate station, direction selector switch means operable by passage of the car by the position of register with the intermediate station, said direction selector switch means being coupled to said intermediate station call signalling means and to the up-direction and down-direction holding circuits for selective energization of the holding circuit corresponding to the direction in which the car must arrive, means for arresting the movement of the car upon the actuation of the direction selector switch means as the car arrives at the calling intermediate station, and direction order control means responsive to a call held prior to the arrival of the car for a station beyond said intermediate station in the direction of arrival of the car thereat for limiting the next operation of the system to further movement of the car to the next station ahead in said direction of arrival at the intermediate station.

29. A control system for a vertical lift apparatus of the type including a hatchway extending between an upper terminal station and a lower terminal station with at least one intermediate station and with a car guided in said hatchway and motor propelled for upward and downward movement therein, the control system comprising: means at each of said terminal stations for signalling calls to bring the car thereto, means coupled to each of said terminal station call signalling means for receiving and holding a call until fulfilled by a stop of the car at the calling terminal station, means at each intermediate station for signalling calls to bring the car thereto, an up-direction intermediate station call holding circuit and a down-direction intermediate station call holding circuit, direction selector switch means operable by passage of the car by the position of register with the intermediate station, said direction selector switch means being coupled to said intermediate station call signalling means and to the up-direction and down-direction holding circuits for

32

selective energization of the holding circuit corresponding to the direction in which the car must arrive, means for arresting the movement of car upon the actuation of the direction selector switch means as the car arrives at the intermediate station in response to a call signalled thereto, means for temporarily disabling said intermediate station call up-direction and down-direction holding circuits from control of the car propelling motor and simultaneously exercising superseding control of the motor to drive the car directly to a desired destination notwithstanding calls to other stations, and means coupled to said holding circuits disabling and superseding control exercising means for replacing an intermediate station up-direction holding circuit condition with a down-direction holding circuit condition when the car is made to ascend past the intermediate station to a destination thereabove and for replacing an intermediate station down-direction holding circuit condition with an up-direction holding circuit condition when the car is made to descend past the intermediate station to a destination therebelow by the exercise of superseding control.

30. A control system for a vertical lift apparatus as defined in claim 29, further including directional order control means for causing the car to proceed in one direction in answering a plurality of simultaneously held calls until no further calling station lies ahead and thereafter relinquishing the direction maintaining control to permit the car to proceed in the reverse direction to answer calls in the reverse direction.

31. A control system for a vertical lift apparatus as defined in claim 30, wherein said directional order control means is superseded by the operation of said temporary disabling and superseding control exercising means and is restored to operation upon the arrival of the car at the superseding control destination and is thereafter active to cause further operation in the direction of the superseding control operation until no call lies further ahead in that direction.

LE ROY H. KIESLING.
